(57) **CLAIM**

The ornamental design for a child resistant cap with air flow orifices as shown and described.

DESCRIPTION

FIG. 1 is a top perspective view of the child resistant cap with air flow orifices according to the present invention;

FIG. 2 is a front elevational view thereof;

FIG. 3 is a rear elevational view thereof;

FIG. 4 is a top plan view thereof;

FIG. 5 is a bottom view thereof;

FIG. 6 is a right side elevational view thereof; and,

FIG. 7 is a left side elevational view thereof.

The broken lines are included for the purpose of illustrating portions of the child resistant cap with air flow orifices and form no part of the claimed design.

1 Claim, 4 Drawing Sheets
